(57) **CLAIM**

The ornamental design for an umbrella base, as shown and described.

DESCRIPTION

FIG. 1 is a perspective view of an umbrella base showing a new design;

FIG. 2 is another perspective view of the design of FIG. 1;

FIG. 3 is a top view of the design of FIG. 1;

FIG. 4 is a rear view of the design of FIG. 1;

FIG. 5 is a front view of the design of FIG. 1;

FIG. 6 is a left side view of the design of FIG. 1; and,

FIG. 7 is a right side view of the design of FIG. 1. The dot-dash line represents a boundary of the claimed design.

The evenly broken lines depict portions of the umbrella base that form no part of the claimed design.
